UNITED STATES PATENT OFFICE.

FRANZ PÜNING, OF CHICAGO, ILLINOIS, ASSIGNOR, BY MESNE ASSIGNMENTS, TO
H. KOPPERS COMPANY, A CORPORATION OF PENNSYLVANIA.

APPARATUS FOR RECOVERING HYDROCARBONS FROM ABSORBING-OILS.

1,176,094.

Specification of Letters Patent. Patented Mar. 21, 1916.

Application filed October 20, 1913. Serial No. 796,130.

To all whom it may concern:

Be it known that I, FRANZ PÜNING, a subject of the German Empire, residing in Chicago, in the county of Cook and State of Illinois, have invented a new and useful Improvement in Apparatus for Recovering Hydrocarbons from Absorbing-Oils, of which the following is a specification.

This invention relates to improvements in apparatus for recovering hydrocarbons from gases and more particularly to apparatus for recovering hydrocarbons, for instance benzol and its homologues, from the used absorbing oils which have received the hydrocarbons from gases of the dry distillation of coal or hydrocarbons from natural gases.

The description in this application will be directed more particularly to apparatus for recovering benzol and its homologues although, as will be understood by those skilled in the art, the apparatus is equally adaptable for recovering other hydrocarbons from absorbing oils.

Briefly outlined, the recovery of the hydrocarbons and especially benzol and its homologues from the dry gases of distillation from coal or other fuel, is as follows: The gases of distillation are first cooled to about 77° F. by passing them through coolers, after which they are passed over washers where they are brought into contact with oils capable of absorbing the benzol constituents at a low temperature and which, by heating to about 266° F. and treating with steam, will release them. Tar oil, straw oil and mineral oils are commonly the oils employed for this purpose. The hydrocarbons, such as benzol and its homologues, are next recovered or distilled from the absorbing or wash oil and it is the apparatus for this purpose to which my invention relates.

As is well known, most oils which are used for absorbing hydrocarbons, such as benzol, have a corrosive effect on metals at high temperature, especially if they contain traces of ammonia absorbed from the gases of distillation of coal, and means must be provided, therefore, to allow the easy and quick repairing, replacement and interchanging of these parts without interrupting the continuous operation of the apparatus.

In plants of large capacity, the amount of heat (which is obtained generally from steam) required for raising the temperature of the wash oil sufficiently to effect the dis-

tillation of the hydrocarbons, is very great and economical operation necessitates as much conservation of this heat as possible.

The main objects of my invention, therefore, are, to provide an apparatus for the purpose above described which will insure the recovery or conservation of as much of the required heat introduced into the wash oil as possible, and to provide an apparatus of simple arrangement which will permit of cheap and quick replacements or repairs or interchange of all those parts subjected to corrosive action.

The invention furthermore consists in the parts and devices and in the novel combinations of the parts and devices as herein shown, described or claimed.

In the drawing forming a part of this specification, Figure 1 is a diagrammatic view of an apparatus embodying my improvements, the still, which is of column type, being shown in section and the other parts in elevation, and Fig. 2 is a longitudinal sectional view showing diagrammatically the general well-known construction of the heat exchangers, superheaters and condensers or coolers; Fig. 3 is an enlarged general view of the apparatus, to show more clearly the relations and construction of the elements indicated in Fig. 1, with parts of the walls of various heating and cooling units broken away to expose more clearly the internal arrangement, and with a considerable portion of the upper part of the column broken away to accommodate it to the space available on the sheet for enlarged illustration of the other elements or units in the apparatus; Fig. 4 is a horizontal sectional view of the heat exchanger A, and also serves to illustrate the general construction of the heat exchanger B and the heat exchanger or cooler G and the colors G¹ and G² and E, except that the said units B and G and G¹ and G² are severally provided also with inlets and outlets for water for cooling (as indicated in Fig. 3); Fig. 5 is a vertical section of the same unit A illustrated in Fig. 4, with some of the parts omitted; Fig. 6 is a transverse vertical section of the same unit A illustrated in Figs. 4 and 5; Fig. 7 is a vertical sectional view of the superheater C; Fig. 8 is a partly sectional and partly top plan view of the same unit C illustrated in Fig. 7; Fig. 9 is an end view of the same unit C, as seen in Figs. 1

- and 3; Fig. 10 is a vertical transverse sectional view of the same unit C; Fig. 11 is a vertical sectional view of the column, which constitutes the still indicated in Fig. 1; Fig. 12 is a section on the line XIII—XII of Fig. 11; and Fig. 13 is a section on the line XIII—XIII of Fig. 11.
- Like reference numerals indicate like parts in the various figures.
- 10 The cold wash oil which is enriched with the hydrocarbons is pumped from the washers, above mentioned, through the pipe 10 into the first heat exchanger or preheater A, Fig. 3. In passing through this heat exchanger, the wash oil is given its first or preliminary heating by the vapors from the column as will be hereinafter described, it being understood that the heat exchanger A is in the form of an ordinary condenser 15 or tank having horizontally arranged tubes or flues as will appear hereinafter, and as more particularly illustrated in Figs. 4, 5 and 6, in which the general flow of the wash oil, around the usual well known arrangement of baffles, and between the pipes that themselves serve as baffles, is indicated by arrows. After passing through the heat exchanger A, the wash oil is then conducted by a pipe 11 to a second heat exchanger or 20 preheater B and in passing therethrough is heated to a still higher degree by the hot oil which comes from the column through the pipe 12, the heat exchanger B being similar to the heat exchanger A, that is, in the form 25 of a horizontally arranged condenser. This heat exchanger B is indicated in Fig. 1 and more particularly shown in Fig. 3, and is of the general construction of the heat exchanger unit A illustrated in Figs. 4, 5 and 30 6 except that it is additionally provided with the water inlet and outlet 26, 26' controlled by suitable cocks, to permit the said heat exchanger B to be used as a cooler for the wash oil from the column if under any 35 circumstances the wash oil going to the column should be passed through the unit G (instead of B) and preheated only in the units A and C or C'. After passing through the heat exchanger B the heated oil is next 40 conducted through the pipe 13 to a superheater C, Figs. 7—10, the latter being of substantially the same construction as the heat exchangers A and B with the exceptions that the tubes therein do not entirely 45 fill the tank but terminate below the top thereof so as to provide a chamber e for the collection of the developed vapors above the top of the level of the liquid therein, and that said superheater C is supplied with live 50 steam through the pipe connections, the steam entering through the inlet 14 and passing off through the outlet 14', after having flowed back and forth through the pipes within the said unit C, as indicated in Figs. 55 7, 8, 9 and 10. In the superheater C, the

wash oil is heated to approximately 266° F. thus causing the vaporization or distillation of part of the hydrocarbons, which part is conducted through the pipe 15 to the upper section of the column D. In this superheater C the vapor given off from the highly heated wash oil is raised to a sufficiently high temperature to maintain it in vaporous condition when it passes off through the long pipe 15 and into the upper portion of the column, compensating the reduction of temperature resulting from the radiation of heat necessarily incident to such flow through the pipe connection and outflow into the interior of the column; and the wash oil flowing from the said superheater C is also raised to a high enough temperature to compensate the loss of heat incident to its subsequent flow through the pipe connections to the column and down through the system of drip pans and baffles within the column,—with the further result that the live steam injected into and flowing up through the column gives up its heat substantially only to effect the distillation of the hydrocarbons rather than to maintain or augment the temperature that is required to be maintained in the wash oil and vapor that have passed into the column from the unit C. The superheated wash oil, after passing through the superheater C, is conducted by branch pipe 16 and pipe 17 to the top part of the lower section of the column. The now very hot wash oil in passing down to the bottom of the column over the drip pans, which are of well-known construction, will give up all of its absorbed hydrocarbons on account of the steam which enters the column at the bottom thereof through the pipe 18 and which flows upwardly through the column in a counter direction to that of the down-flowing oil. The general manner of flow of the steam injected into the column is indicated by the arrows in Fig. 11; and the descending oil, from which the hydrocarbon vapor is being distilled, passes downward, in reverse direction, by the same general course, through the apertures in and around the drip pans and horizontal baffles in the column. The hydrocarbon vapors thus formed rise and mingle with those which are conducted to the column through the pipe 15 and all are drawn off mixed with the steam through a pipe 19 which conducts the heated vapors to the first heat exchanger A. The vapors in passing through the latter will heat the wash oil, as previously described, and most of the vapors will be condensed in this heat exchanger. The vapors which remain uncondensed and the condensates pass from the heat exchanger A through a pipe 20 (as indicated more particularly in Figs. 3, 4 and 5) to a cooler or condenser E which is cooled by water introduced through pipe 100 105 110 115 120 125 130

21 and passing off through the outlet pipe 21'. The complete condensation of the steam and vapors is effected in the cooler E and the condensates—water and recovered hydrocarbons—are conducted through pipe 22 to a separator F, where the water and hydrocarbons are separated by gravity, the hydrocarbons passing off through a pipe 23 to a storage tank (not shown), after which 10 the recovered hydrocarbons are fractionated into their components; and the water separated passes out through the pipe 24.

The construction and arrangement of the coolers G, G¹ and G² are more particularly 15 shown in Fig. 3. Each of these units has the same general construction that is shown for the unit A illustrated in Figs. 4, 5 and 6, except that the unit G is additionally provided with the cold water inlet 26 and outlet 26', to permit the said unit to be used as a cooler for the wash oil from the column when the wash oil passing to the column is flowing only through the unit B. The units G and G², however, may omit the connections for the wash oil flowing to the column, such connections being provided only on the otherwise identical units B and G, as also 20 illustrated in Fig. 3. The wash oil flowing from the column may be cut off from any 25 one or more of the units B, G, G¹ or G² by the cocks indicated in Fig. 3. And the wash oil flowing to the column may be cut off from either of the units B or G, or may be caused 30 to flow in parallel or in series through both 35 of them, by appropriate manipulation of the cocks illustrated in the connections shown in Fig. 3. In said figure, the general direction of flow, when the appropriate cocks are opened or closed respectively, is indicated 40 by arrows in said Fig. 3 and will be apparent upon inspection of such indication.

The column is made of cast iron, as is customary, and consequently is not corroded to any appreciable extent by the heated oils 45 and hence there is practically no danger of the apparatus being shut down for repairs to the column. On the other hand, however, the heat exchangers, superheaters, and coolers must be of very strong construction 50 and steel is generally used for this purpose, and steel is affected by the heated oils and relatively easily corroded; and hence means must be provided to permit of the repair or cutting out of any one of these 55 parts without necessitating shutting down the apparatus. To this end, I provide a spare unit or auxiliary superheater C' Fig. 3 arranged to be connected, either in parallel or in series with the superheater C so that 60 by opening and closing the proper valves in the various pipe connections, as will be clearly understood from the drawing, either superheater may be used independently of the other. In case of a failure in the heat 65 exchanger B, the cooler G (which ordinarily

is used as a water cooler for the heated oil coming from the column and heat exchanger B) may be substituted for the heat exchanger B by opening and closing the proper valves, as will be understood. In 70 case of a failure or breakdown in the heat exchanger A, the cooler G will be used in conjunction with the heat exchanger B and operated in parallel or in series therewith (as above mentioned and as indicated in 75 Fig. 3). In this case, the vapors from the column will be condensed in the cooler E instead of in the heat exchanger A as ordinarily. Other oil coolers G¹ and G² are provided to cool the oil from the column to 80 a low enough temperature so that when the oil is forced through the washers (hereinbefore referred to) the oil will easily absorb the hydrocarbons from the gases of distillation, the cooled oil being conducted to said 85 washer through the pipe 25.

Ordinarily, the oil coolers G, G¹ and G² are water cooled by means of the water introduced through pipes 26 and passing off through pipes 26', but when the cooler G is 90 used to take the place of either of the heat exchangers A or B, water will not be used in such substitute unit, but the exchange of heat will be from oil to oil.

In Fig. 2 is illustrated roughly one of the 95 heat exchangers, the same as shown comprising a horizontal tank 27 having chambers 28 at each end thereof, crown sheets 29 and horizontally extending straight tubes or flues 30. Inlets and outlets for one of the 100 mediums passing through the tank are shown at 31, 31' and the outlets and inlets for the other medium which circulates around the tubes or flues are shown at 32, 32'. As before indicated, the superheaters 105 C, C' are constructed in the same manner as the heat exchangers with the exception that a vapor chamber is provided. And the coolers E, G, G¹ and G² are also constructed similarly to the heat exchangers A and B. 110

As we have also before indicated, the cooler G is constructed in the same manner as the heat exchanger unit A illustrated in Figs. 4, 5 and 6, except for the provision of the supplementary water inlet and outlet 26, 115 26'; and the coolers G¹ and G², for the final outflow of the wash oil from the column, are constructed in the same manner as the cooler G or heat exchanger B except for the omission of the connections and inlet and outlet 120 for wash oil flowing toward the column; and the condensate cooler E has the same construction as either of the coolers G¹ or G²,—as will be apparent upon inspection of Fig. 3.

Although I have herein shown and described what I now consider the preferred embodiment of my improvements, yet as will be understood various changes, modifications and arrangements of parts may be 130

made without departing from the spirit of the invention, and all such changes, modifications and arrangements are contemplated as come within the scope of the claims appended hereto.

I claim:

1. An apparatus for distilling hydrocarbons from an absorbing oil, which includes, in combination: a still; a heat exchanger 10 through which the oil is first passed, said heat exchanger being heated by vapors from the still; a second heat exchanger through which the oil is passed, said second heat exchanger being heated by hot oil from the still; a superheater through which the oil is passed after leaving said second heat exchanger, said superheater being steam heated; a cooler in communication with the first named heat exchanger; and pipe connections 15 between said parts all so arranged that the vapors and heated oils are conducted separately from the superheater to the still and vapors from the latter through the first heat exchanger and the condensates 20 from the latter to the cooler, substantially as specified.

2. An apparatus for the continuous distillation of hydrocarbons from an absorbing oil, which includes a still, a heat exchanger, 30 a superheater, a cooler, and connections between said parts arranged to conduct the oil first through the heat exchanger and through the superheater and from the latter to the still and the vapors from the superheater to the still and the vapors from the still to the heat exchanger and the condensates from the latter to the cooler, said heat exchanger, superheater and cooler each comprising a horizontally disposed tank having 35 straight tubes therein, substantially as specified.

3. An apparatus for the distillation of hydrocarbons from an absorbing oil, which includes, in combination: a still; two heat 45 exchangers arranged in series, the first of which is heated by vapors from the still and the second is heated by oil from the still; a superheater to which the oil is conducted from said second named heat exchanger, said 50 superheater being steam heated; and a second superheater arranged in parallel with the first named superheater whereby either superheater may be interchangeably used to permit of repairs without shutting down the 55 apparatus, substantially as specified.

4. An apparatus for the continuous distillation of hydrocarbons from absorbing oil, which includes, in combination: a still; two heat exchangers arranged in series, the 60 first being heated by vapors from the still and the second being heated by oil from the still; a third heat exchanger arranged to be substituted for either of the first two heat exchangers; a superheater, said superheater being steam heated; pipe connections be-

tween said second and third named heat exchangers adapted to conduct the oil to the superheater; and pipe connections from the superheater to the still adapted to separately conduct the heated oil and the vapors thereto, substantially as specified. 70

5. An apparatus for the continuous distillation of hydrocarbons from an absorbing oil, which includes a still, a heat exchanger heated by vapors from the still, a 75 superheater heated by steam, said superheater having a chamber at the top thereof adapted to collect the developed vapors therein; a cooler adapted to receive the condensates from said heat exchanger; and pipe connections from the superheater to the still adapted to separately conduct the developed vapors and heated oil thereto, substantially as specified. 80

6. An apparatus for the continuous distillation of hydrocarbons from absorbing oil, which includes two heat exchangers, a superheater and a still connected by pipes and arranged in series so that the absorbing oil is passed first through one heat exchanger, then through the second heat exchanger, then through the superheater and from the latter to the still, and connections from the still to the heat exchangers so arranged that the first heat exchanger is 90 heated by vapors from the still and the second heat exchanger is heated by oil therefrom, substantially as specified. 95

7. An apparatus for the continuous distillation of hydrocarbons from an absorbing oil, which includes, in combination: a still; a heat exchanger A heated by vapors from the still; a heat exchanger B heated by oil from the still; a steam heated superheater C, the latter being in communication 100 with the heat exchanger B and from which it receives the oil, said superheater having a vapor chamber c in communication with the still and having also another connection with the still for the heated oil; and a water-cooled cooler E adapted to receive the condensates from the heat exchanger A, substantially as specified. 105

8. An apparatus for the continuous distillation of hydrocarbons from absorbing oil, which includes, in combination: a still; a heat exchanger, arranged to be heated by vapors from the still; a superheater connected in series with said heat exchanger, said superheater being steam heated; a second superheater connected by pipe connections so as to be arranged either in series or in parallel with the first superheater, said second named superheater being steam heated; and connections from the superheaters to the still, substantially as specified. 115

9. An apparatus for continuous distillation of hydrocarbons from an absorbing oil, 120

- which includes, in combination: a still; a
succession of heaters for heating the oil,
first, by the vapors leaving the still, second,
by the hot oil leaving the still, and then, by
5 live steam; the heaters being so intercon-
nected that such heater units are adapted to
be interchanged to permit repair and re-
placement without disturbing the operation
of the system; and connections for convey-
10 ing the oil successively through the heaters
to the still, and for conveying the vapors
and the hot oil from the still to the respec-
tive vapor-heated and oil-heated heaters, and
for conducting live steam to the steam-
15 heated heaters; substantially as specified.
10. An apparatus for continuous distilla-
tion of hydrocarbons from an absorbing oil,
which includes, in combination: a still; a
succession of horizontally disposed heaters,
20 fitted with substantially straight standard

tubes, for heating the oil, first, by the vapors
leaving the still, second, by the hot oil leav-
ing the still, and then, by live steam; the
heaters being so interconnected that such
heater units are adapted to be interchanged
25 to permit repair and replacement without
disturbing the operation of the system; and
connections for conveying the oil success-
ively through the heaters to the still, and
for conveying the vapors and the hot oil
30 from the still to the respective vapor-heated
and oil-heated heaters, and for conducting
live steam to the steam-heated heaters; sub-
stantially as specified.

Signed this 17th day of October, 1913, in 35
the presence of two witnesses.

FRANZ PÜNING.
